UNITED STATES PATENT OFFICE.

EDWARD H. TAYLOR, OF PATERSON, NEW JERSEY, ASSIGNOR OF ONE-HALF
TO ROBERT ADAMS, OF NEW YORK, N. Y.

WARP-BEAMING MACHINE.

SPECIFICATION forming part of Letters Patent No. 423,643, dated March 18, 1890.

Application filed August 21, 1889. Serial No. 321,487. (No model.)

To all whom it may concern:

Be it known that I, EDWARD H. TAYLOR, of the city of Paterson, in the county of Passaic and State of New Jersey, have invented 5
a new and useful Improvement in Warp-Beaming Machines, of which the following is a specification.

My improvement relates to beaming attachments for warping-mills adapted to beam 10 narrow warps for looms.

The following is a description of my improvement in detail:

In the accompanying drawings, which form 15 a part of this specification, and in which similar letters of reference indicate like parts, Figure 1 is a side elevation of a warp-beaming machine. Fig. 2 is a front elevation of part of the same, showing the beaming attachment embodying my invention. Fig. 3 is a 20 plan of one of the adjustable heads and supports therefor. Fig. 4 is a front sectional elevation of part of the same. Fig. 5 is a side view thereof in section. Fig. 6 is a side elevation, partly in section, of part of my warp-beaming machine. Fig. 7 is a front elevation 25 of part of the same.

The frame and reel of the warping-mill A may be of any desired construction. The warp Z is wound from the reel D to and upon 30 a series of beams E E, Figs. 2 and 7, and any desired number of beams may be employed. The beams are held in line partly by means of a rod k, which passes axially through them, and partly by driving-studs f² in disks f, 35 mounted upon a number of hollow shafts k², which hollow shafts are journaled in movable standards g, each standard g being provided with an oil-hole g'. As many movable standards may be employed as are necessary for 40 the number of beams desired to be wound. The beams and movable standards alternate, and each of the disks or plates f has a slot f³, in which the driving-stud f² is secured by means of a nut f', and in which the stud f² 45 is capable of being adjusted for the purpose of driving a large or small beam, as the case may require. The stud engages the head of the beam and causes the beam and disk to revolve together. The movable standards g g 50 are mounted on the frame or bed A', which is constructed, as shown in Figs. 5 and 6, with a longitudinal opening or slot A⁵. Each standard is mounted on a sole-plate h, which

is secured to the frame A' by means of the screw h⁸, which passes through the opening or slot A⁵ in the frame A' and into the bottom or sole-plate h of the standard, and has on the lower end thereof the washer-plate h⁴ and wing-nut h⁵, as shown in Figs. 2, 5, 6, and 7. On the sole-plate h of each standard plates h' h' are secured by screws h⁶, said plates being beveled on their inner edges, as shown in Fig. 4, so as to permit the standard g to slide between them on the sole-plate h. A screw h² passes through a threaded lug on 65 the sole-plate, and its plain end is held in a socket in the standard by a screw h⁸, the end of which enters a groove in the end of screw h².

In Figs. 2, 6, and 7 of the drawings, b⁴ represents a cone-pulley secured to one end of 70 one of the hollow spindles k². The cone-pulley b⁴ is caused to revolve either by means of the belt x, which passes from the cone-pulley b⁸ on line-shaft b² to said cone-pulley b⁴, as shown in Fig. 7, or it receives its motion 75 from a belt b²⁶, which passes from the main driving-pulley b' on shaft b² to pulley b, which is mounted on shaft b⁵ and is fast to the pinion c, which is thereby revolved, the pinion c engaging the gear-wheel d, which 80 is mounted on one end of a hollow shaft k², journaled in the collar a³ of the bracket a, which is secured to one end of the frame A'. The pinion c thus revolves said hollow shaft k² and its driving-plate f, which is secured to the other end thereof and carries a stud f², which engages with the cone-pulley 85 b⁴. To prevent the gear-wheel d from rotating in a wrong direction, I employ the pawl e, which is mounted in the standard a'. A loose 90 pulley b²⁶ is mounted at the side of pulley b. The beams are apt to get out of line sometimes and impede the working of the machine, and to obviate that difficulty the standards g are constructed so as to be easily moved 95 backward or forward, as occasion requires, on the sole-plates h between the side plates h' by manipulating the set-screws h². Motion given to the driving-pulley b from pulley b', located on the line-shaft b², is thence transmitted to the gear-wheel d, located on the head a³, by the pinion c. The disk or driving-plate f, mounted on the shaft k² of the wheel d, by means of its stud f², communicates a rotary motion to the cone-pulley b⁴ on 100 the second shaft k². On the other end of 105

this shaft is a second plate f , which, by means of its stud f^2 , imparts a rotary motion to the first beam E , which revolves on the rod k , which latter passes through all the beams E 5 and hollow shafts k^2 . The first beam E , being in motion, imparts to the third plate f at its other end, by means of a similar stud f^2 , a rotary motion, and thus throughout the beams of the series, Figs. 2 and 7. The adjustment 10 for the lengths of the beams E is made by moving the standards g nearer together or farther apart on the bed A' and fastening them in position by the holding devices described. Adjustment transversely is effected 15 by moving the standards g into line by the screws h^2 . The warp-threads Z having been attached to the beams E in a suitable manner, on the system of beams E being put in motion the warp Z is unwound from the reel D , 20 which revolves in bearings B in the frame A^2 , Figs. 1 and 6, and is wound upon the beams E until the beams are filled. Then the machine is stopped, the warp cut, and the filled beams are taken out by withdrawing 25 the wire or rod k and slackening the studs f^2 . Empty beams now are inserted, the wire or rod k and studs f^2 are readjusted, and the machine is again started and the operation repeated.

30 To operate for edge warping or beaming, the belt from the pulley b' is shifted from the pulley b to the loose pulley b^2 , the stud f^2 is removed from the first disk f on the shaft k^2 , which is held in the collar a^3 , and a belt x is put on the cone-pulleys $b^3 b^4$, whereby motion is imparted to the disks or plates f and to the system of beams E before described. A more or less rapid motion is imparted by arranging the belt x on the larger 35 or smaller surfaces of the cones $b^3 b^4$, the filling of the beams E from the reel D being much more rapid than with the gearing system before described, by reason of the motion being taken direct from the line-shaft b^2 instead of being communicated through 40 the gearing-wheel and pinions c and d .

With this description of my invention, what I claim is—

1. The combination, with driving mechanism, of a number of hollow shafts to which 45 are secured disks provided with driving-studs adapted to engage the opposite heads of beams upon which warp is to be beamed, whereby motion is transmitted throughout 50 the series, a rod which passes through the beams and hollow shafts, movable standards in which said hollow shafts are journaled, sole-plates on which said standards are mounted, a bed for supporting the sole-plates, 55 and on which they may be moved lengthwise, devices for securing each sole-plate in adjusted position on the bed, plates mounted 60 on each sole-plate and beveled on their inner edges to hold the corresponding standard, 65 and a screw for adjusting the standard on the sole-plate, substantially as specified.

2. The combination, with a line-shaft hav-

ing a cone-pulley and a driving-belt, of a series of hollow shafts provided with disks or plates carrying driving-studs, one of said 70 shafts having secured on one end thereof a cone-pulley, a wire or rod passing axially through the hollow shafts and adapted to pass also through the beams placed between said disks, means for securing each of the driving-studs adjustably upon its carrying-disk, 75 movable standards in which said hollow shafts are journaled, a sole-plate on which each standard is mounted, devices for holding said standards in adjusted position upon the supporting bed or frame, and devices for adjusting each standard laterally upon its sole-plate, substantially as specified.

3. The combination, with the line-shaft carrying a cone-pulley and a belt, of a frame or 85 bed, a number of standards, sole-plates supporting said standards and movable lengthwise along said bed or frame, devices for securing said sole-plates in adjusted position, side plates having the inner edges thereof 90 beveled and mounted upon the sole-plates, the standards fitting between said side plates, a screw for adjusting each standard laterally, 95 a number of hollow shafts journaled in said movable standards, one of said hollow shafts having a cone-pulley on one end, disks secured to the ends of said hollow shafts and each provided with a slot to receive a driving-stud, a driving-stud adjustably secured in each of said slots by means of a nut, and a 100 rod or wire passing through the series of hollow shafts and the beams placed between the disks thereof, all constructed substantially as shown and described, and for the purposes stated.

4. The combination, with driving mechanism having a gear-wheel, of a number of hollow shafts, one of which is provided at one end with a gear-wheel in mesh with the gear-wheel of the driving mechanism and at the 110 other end with a driving-disk having a driving-stud secured therein, the adjoining hollow shaft of the series carrying a part adapted to be engaged by said driving-stud, disks mounted on the other end of this 115 shaft and on each end of each of the remaining hollow shafts and provided with driving-studs, a rod or wire passing through the whole series of hollow shafts and the beams placed between the disks, a number of movable standards in which said hollow shafts are journaled, a sole-plate for each of the 120 standards, side plates on each of said sole-plates for guiding the standards, a screw for adjusting each of the standards between said 125 plates, the bed or frame, and devices for securing each of said sole-plates to the bed or frame, substantially as and for the purposes specified.
